WOODEN FORK OR SIMILAR ARTICLE

Jose M. Figueras, Manila, Philippines, assignor to Overseas International, Inc., Redwood City, Calif.

Filed Feb. 17, 1964, Ser. No. 78,667

Term of patent 14 years

(Cl. D54—12)

FIG. 1 is a front elevational view of my design for a wooden fork.

FIG. 2 is a side elevational view of the fork of FIG. 1.

FIG. 3 is a rear elevational view thereof.

The essential features of my design reside in the handle portion, as shown.

I claim:

The ornamental design for a wooden fork or similar article, as shown and described.
